(57) **CLAIM**

The ornamental design for the computer, as shown and described.

DESCRIPTION

FIG. 1 is a front elevational view of the computer showing our new design;

FIG. 2 is a rear elevational view thereof;

FIG. 3 is a left side elevational view of one side thereof;

FIG. 4 is a right side elevational view of the other side thereof;

FIG. 5 is a top plan view thereof;

FIG. 6 is a bottom plan view thereof;

FIG. 7 is a perspective view thereof; and,

FIG. 8 is a cross-sectional view thereof taken along line 8-8 of FIG. 1 omitting the inner mechanisms.
